CLAIM

The ornamental design for a high end cable connector assembly, as shown and described.

DESCRIPTION

FIG. 1 is a front perspective view of a high end cable connector assembly, showing my new design;

FIG. 2 is a side view thereof; the opposite side of the view shown in FIG. 2 is a mirror image of the side view shown; FIG. 3 is a top view thereof; and,

FIG. 4 is a rear perspective view thereof.

The broken lines showing of the environment in FIGS. 1 through 4 are for illustrative purposes only and form no part of the claimed design.
